UNITED STATES PATENT OFFICE.

JOHN R. THOMAS, OF CINCINNATI, OHIO, ASSIGNOR TO J. A. FAY & EGAN COMPANY, OF CINCINNATI, OHIO, A CORPORATION OF WEST VIRGINIA.

PLANING MACHINERY.

No. 821,137.

Specification of Letters Patent.

Patented May 22, 1906.

Application filed March 30, 1905. Serial No. 252,927.

To all whom it may concern:

Be it known that I, JOHN R. THOMAS, a citizen of the United States, residing at Cincinnati, in the county of Hamilton and State 5 of Ohio, have invented certain new and useful Improvements in Planing Machinery, of which the following is a specification.

My invention relates to planing machinery including so-called "wood planing and matching machines, flooring-machines, molding-machines," and the like, and has for its object the providing of new and improved yielding-pressure means for the stock being operated on by a side cutter-head, which pressure means form a holddown device for the stock for definitely positioning it for operation thereon by a side cutter-head, while offering minimum resistance to the feed of said stock; and my invention has for its further object the providing of a new and improved chip-breaker for a side cutter-head in such machinery.

My invention consists in providing a new and improved pressure mechanism having an idler-roll arranged to be swung out of the way and taking against the stock for positioning the stock for operation thereon by a side cutter-head; further, in providing a chip-breaker for a side cutter-head which has a journal connection concentric to the rotary axis of the side cutter-head; further, in providing a contact-roll device for the chip-breaker having a actuating connection with the chip-breaker, whereby the chip-breaker is caused to recede by the receding movement of the contact-roll in such manner that the toe of said chip-breaker is maintained laterally in similar relation to said roll, and the invention will be further readily understood from the following description and claims, and from the drawings, in which—

Figure 1 represents a side elevation of so much of a planing-machine as is necessary to illustrate my invention and having my improved device connected therewith. Fig. 2 is a plan view of the same. Fig. 3 is a vertical cross-section of the same, taken on the line *x x* of Fig. 2. Fig. 4 is a sectional detail, partly broken away, taken on the line *y y* of Fig. 2; and Fig. 5 is a detail in side elevation of the bridge-support.

The machine-frame 1 has a cross-support 2, upon which side cutter-head hangers 3 4, also known as "matcher-hangers," are ad-

justed sidewardly, as by means of adjusting-screws 5 6. The matcher-hangers, respectively, have side cutter-head spindles 7 8 journaled thereon in proper bearings, the spindles carrying side cutter-heads 9 10. The lower ends of the matcher-hangers and spindles are broken away and not shown because well known.

Standards 11 12 project upwardly from the main frame and support a cross-shaft 13 in bearings 14 15, the same being secured in place by means of a set-bolt 16. A bridge 17 has a bearing 18 about the cross shaft or rod 13, collars 19 20 being secured to the shaft by set-bolts 21 22 to either side of the bearing 18 for positioning said bearing longitudinally of the shaft—*i. e.*, transversely of the main frame—to correspond to the sidewise adjustment of the hanger 3. This shaft or rod may be moved longitudinally for releasing the bridge from the machine and may be provided with a pull-handle 23, and the bridge may be swung upon its bearing 18 about the rod for swinging said bridge, the roll or rolls supported thereby, and the roll-slide upon which the latter are mounted in manner hereinafter described out of the way of the side cutter-heads for permitting access to said side cutter-heads.

A roll-slide 26 slides in a guideway 27 on the bridge and is adjustable up and down thereon by a screw-rod 28, having threaded connection 29 in a lug 30 of the bridge and journal connection in a lug 31 of the slide, a hand-wheel 32, having spline connection 33 with said screw-rod, being arranged to turn the screw-rod. The upper end of the screw-rod is also threaded, as shown at 34, a nut 35 screwing thereon for adjusting a spring 36 (shown as a volute spring) taking about the screw-rod between the lug 31 of the slide and a washer 37 taking against the hand-wheel, a collar 38 being on the screw-rod for limiting the downward movement of the slide. The bridge may have a recess 39 for receiving the screw-rod. A stud 41 is rigidly secured in a bearing 42 on the slide, as by being threaded thereto, and has a hanger 43 rigidly secured thereto at its outer end, as by a set-bolt 44. A roll-stud 45 is rigidly secured to the slide, as by being threaded thereto, and has a support at its outer end in a bearing 46 on the hanger 43. The roll stud or shaft may support one or more rolls 48, which may be con-

75

veniently removed or replaced by releasing the set-bolt 44, whereby the hanger may be slid endwise and turned out of line with the rolls on the stud 45 for permitting insertion, 5 removal, or substitution of the pressure-rolls 48 or, as they may be termed, "pressure-roll sections," said pressure-roll or roll-sections being preferably idlers journaled on said stud. The roll-sections are preferably 10 narrow, and one or more roll-sections may be employed on the stud, depending on the width of pressure agency it is desired to have, filling-up collars 49 being employed to position the roll-sections upon their stud.

15 The matcher-hanger 3 has a shelf 51 secured thereto, upon which there is an upward projection 52, to which an eyebolt 53 is pivoted on a pin-bolt 54. The bolt 53 is adapted to take through a slot 55 in the 20 bridge, a nut 56 and washer 57 taking above the walls of the slot about the bolt for rigidly securing the bridge in position.

If it is desired to get at the side heads or 25 their chip-breaker or at other parts of the machine obstructed by the pressure-roll device, the nut 56 is relieved and the bolt 53 swung out of its slot, which permits the bridge 17 to swing upon its bearing about the shaft 13, thereby swinging the bridge, slide, and 30 rolls clear and out of the way of the matcher-heads, their hangers, and chip-breakers. The device occupies little longitudinal space in the machine, it provides an overhanging idler-roll pressure for the stock at the matcher-heads, it is firm in construction and operation, 35 provides strong pressure closely adjacent the point at which the stock receives the pounding of the knives of the side heads, and enables pressure-rolls of large diameter to be 40 employed and offers minimum resistance to the feeding of the stock.

In machines of the character mentioned the right-hand matcher-head when standing facing the feeding-out end of the machine is 45 usually the positioned matcher-head, being positioned adjacent the point across the machine at which it is desired to have the stock travel, the left-hand matcher-head being adjusted for the width of the stock it is desired 50 to cut. The matcher-head 9 is shown as the positioned matcher-head and the matcher-head 10 as the adjustable matcher-head. These matcher or cutter heads are shown as cutting opposite each other, and my improved construction of holddown device permits this to be done, holding the stock down 55 firmly to the bed without exerting undue resistance to the feed of the stock and permitting stock having perfectly parallel sides to 60 be produced. The bridge 17 preferably spans the positioned matcher-head, taking above the same. A rigid chip-breaker 58 is secured to the shelf 51 by means of bolts 59, threaded to the shelf and taking through 65 slots 60 in the rigid chip-breaker for permit-

ting its adjustment, a backing-bolt 61, threaded to the upward extension 52 of the shelf, taking against the chip-breaker for positioning the same, the stock taking against the chip-breaker 58 closely adjacent the pressure-rolls. A shaving-hood 62, secured to shelf 51 by bolts 62', may take over the side cutter-head. The rigid chip-breaker may form part of the side gage of the machine.

The adjustable match-hanger 4 has a shelf 63 rigidly secured thereto. The cutter-spindle 8 takes through this shelf. A swinging chip-breaker 65 is journaled about said spindle concentrically with the circle of cut of its cutter-head. Thus the shelf is provided 80 with an annular rabbet 66 and the swinging chip-breaker with an annular rabbet 67, forming a depending journal-piece 68. The walls of said rabbets are concentric to the circle of cut of the cutter-head and form 85 a runway 69 for antifriction-balls 70, disposed in the runway, thereby forming a roller-bearing upon which the chip-breaker swings concentrically to the circle of cut of its cutter-head. The ball-bearing bears the 90 weight of the chip-breaker. Suitable retaining-pieces 71 are secured to the end of the journal-piece on the swinging chip-breaker and take under the shelf for retaining the swinging chip-breaker upon the shelf. 95

The swinging chip-breaker may be provided with a toe 72, which is preferably adjustable and separable. The toe is adjustable in a slot 73 and retained in adjusted position by bolts 74. A bolt 76 screws into a 100 lug 77 of the swinging chip-breaker and takes against the shelf 63 for limiting the inward movement of the chip-breaker toe. The contact-face 78 of the toe is preferably beveled, so that the extreme outer edge of the toe may 105 take lightly against the stock throughout its various swinging positions.

A lever 81 has a part thereon adapted to be contacted by the stock and is arranged to cause receding of the swinging chip-breaker. The lever 81 is pivoted on a bolt 82, secured to the shelf 63, and a roll 83 is journaled on a stud 84, secured in the swinging end of said lever. The inner edge of the stock-contacting face of this roll is preferably positioned at 115 a slightly less distance from the longitudinal middle of the machine than the inner edge of the toe 72. Constructed in this way the roll bears the impact of the swinging chip-breaker against the stock, the roll in practice pressing 120 slightly into the stock and permitting the toe to bear lightly against the stock and perform its office of breaking the chips relieved of the duty of primarily yielding to inequalities in the stock. The roll forms a swinging movable heel for the swinging chip-breaker whose pivot is disconnected from the said chip-breaker. The roll 83 bears upon an inclined face 85 of the swinging chip-breaker. This inclined face merges into a stop 86, taking 130

against the roll when the parts are in normal position. A cable 87 is secured to the lug 77 on the swinging chip-breaker and takes over a wheel 88 on a stud 89, secured to the shelf 63. The cable has a weight 90 secured thereto. These parts act to normally press the roll 83 and the toe 72 toward the stock for bearing against the latter and provide the necessary pressure against which the roll and toe yield to inequalities in the stock. The chip-breaker may be in the form of a shaving-hood 91, having a cover 92 and a mouth 93. A projection 94 on the shelf 63 prevents the lever 81 overthrowing inwardly into the machine. The shelf 51 has a rabbet 95, in which is a support 96, and the shaft 63 has a rabbet 97, in which is a support 98 for the stock passing through the machine, the supports forming part of the table or bed of the machine.

The length of the contact-roll lever, the location of its pivotal point, and the angle of the inclined face on the chip-breaker are relatively such as to cause the inner edge of the contact-face of the contact-roll and the inner edge of the chip-breaker to yield to equal extent throughout the various degrees of yield to inequalities in the stock, thereby maintaining the inner faces of the movable heel and the toe of the chip-breaker in a plane substantially parallel with the direction of feed of the stock, the toe of the chip-breaker being maintained closely adjacent and concentric to the circle of cut of the cutter-head, the contact-roll device forming a friction-releasing member between the stock and chip-breaker.

The pivotal point of the lever is preferably located inwardly of a right line drawn between the rotary axes of the cutter-spindle and contact-roll and the inclined face is preferably at an angle to said right line and the direction of projection of said lever.

My improved holddown device and chip-breaker, the means for causing primary receding of the latter, and the relative disposition of the same are peculiarly effective in operating on stock fed at a high rate of speed past the cutter-heads.

The side gage-piece 101 is adjustably secured to the shelf 51 by a bolt 102, taking through a slot 103 in said side gage-piece and into said shelf 51, a backing-bolt 104 being threaded into a lug 105 on the shelf 51 and taking against the gage-piece for positioning the latter. The guide-piece 106 is adjustably secured to the shelf 63 by a bolt 107, taking through a slot 108 in said guide-piece and into the shelf, a backing-bolt 109 being threaded into a lug 110 on the shelf 63 and taking against the guide-piece.

Having thus fully described my invention, what I claim as new, and desire to secure by Letters Patent, is—

1. In a planing-machine, the combination with a side cutter-head, of a holddown de-

vice comprising a swinging bridge extending longitudinally of the machine and arranged to swing away from the side cutter-head, a slide on said bridge intermediate of its ends, and a pressure-roll mounted on said slide and adapted to take against the stock closely adjacent to said side cutter-head.

2. In a planing-machine, the combination with a side cutter-head, of a swinging bridge taking thereover, means for securing said bridge rigidly in position, and an overhanging pressure-roll yieldably mounted on said bridge.

3. In a planing-machine, the combination of a side cutter-head, a swinging bridge taking thereover, means for rigidly positioning said bridge, a slide on said bridge, means for adjusting said slide up and down, pressure means for said slide, and overhanging idler pressure-roll sections removably mounted on said slide, substantially as described.

4. In a planing-machine, the combination of oppositely-disposed side cutter-heads, a swinging pressure-frame, a slide on the pressure-frame, an idler pressure-roll mounted on said slide, said roll arranged to take against the stock between the said side cutter-heads, means for adjusting said slide up and down, a pressure means for said roll, and means permitting said roll and frame to swing away from the said side cutter-heads.

5. In a planing-machine, the combination with the frame, a pair of standards, a longitudinally-movable shaft, a bridge having a bearing therefor about said shaft, said bridge swinging on said bearing, means for positioning said bridge longitudinally of said shaft, means for positioning said bridge rigidly with relation to the frame, a slide having connection on the said bridge, means for adjusting said slide, pressure means for said slide, an overhanging stud on the said slide, a bearing depending therefrom, a shaft mounted on said slide and in said bearing, and pressure-roll sections removably mounted about said shaft, said last-named bearing being releasable for permitting removal of said roll-sections, substantially as described.

6. In a planing-machine, the combination with a side cutter-head, of a chip-breaker therefor, and roller-bearing for said chip-breaker taking concentrically about the rotary axis of said side cutter-head.

7. In a planing-machine, the combination with a side cutter-head, of a chip-breaker therefor, a roller-bearing for said chip-breaker taking concentrically about the rotary axis of said side cutter-head, said chip-breaker having a toe and an inclined face, a lever, and a contact-roll for said lever taking against said inclined face, the inner edge of said roll maintained slightly nearer the longitudinal middle of the path of travel of stock through said machine than said toe, substantially as described.

8. In a planing-machine, the combination with a side cutter-head, of a chip-breaker therefor, its toe, a lever having a pivot disconnected from said chip-breaker, and a bearing part on said lever for stock, said lever having a part thereon arranged to move the chip-breaker, and flexible pressure means for said chip-breaker, substantially as described.
9. In a planing-machine, the combination with a side cutter-head, of a chip-breaker, a bearing therefor concentric with relation to the rotary axis of said side cutter-head, and a contact-lever for the stock, said chip-breaker having an inclined face, a contact part on said lever taking against said inclined face, and pressure means acting on said chip-breaker for urging the latter simultaneously against said contact part and the stock, substantially as described.
10. In a planing-machine, the combination of a side cutter-head, a chip-breaker, a bearing for said chip-breaker concentric with relation to the rotary axis of said side cutter-head, a lever having a pivot disconnected from said chip-breaker, said lever having a contact part thereon, the chip-breaker having an inclined face therefor, the pivot of said lever being out of a right line drawn from the rotary axis of said cutter-head to said contact part, and said inclined face being projected in a direction traversing said right line and the direction of projection of said lever.
11. In a planing-machine, the combination of a side head-hanger, a side cutter-head mandrel journaled thereon, a chip-breaker, a bearing therefor concentric to said mandrel, a lever pivoted on said hanger, said chip-breaker having an inclined face and said lever having a contact part taking against said inclined face for receding said chip-breaker, and pressure means acting on said chip-breaker for urging the latter simultaneously against said contact part and the stock, substantially as described.
12. In a planing-machine, the combination of a side cutter-head hanger, means for adjusting the same transversely of the machine, a side cutter-head spindle journaled in said hanger, a shelf for said hanger, a yielding chip-breaker, said chip-breaker having a stock-contacting toe, a bearing for said chip-breaker taking concentrically about the rotary axis of said side cutter-head spindle, a lever pivoted to said shelf, a contact-roll for stock thereon, said chip-breaker having an inclined face for said roll, the pivotal point of said lever and the angle of incline of said inclined face being relatively such as to maintain the inner edge of said contact-roll a slightly less distance from the longitudinal middle of stock passing through said machine than the stock-contacting face of said toe, substantially as described.
13. In a planing-machine, the combination of a side head-hanger, a mandrel journaled thereon, a chip-breaker having roller-bearing on the said hanger taking concentrically about said mandrel, said chip-breaker having an inclined face and a stop at the outer end of said inclined face, a lever pivoted on said hanger, a contact-roll mounted on the swinging end of said lever, the outward movement of said roll normally limited by said stop, said roll arranged to move along said inclined face for swinging said chip-breaker about its concentric bearing, substantially as described.
14. In a planing-machine, the combination of a side head-hanger, a side cutter-head spindle journaled therein, a side cutter-head chip-breaker, a concentric bearing for the latter taking concentrically about the rotary axis of said spindle, said chip-breaker having a toe, and a contact part for the stock and said chip-breaker, the inner edge of said contact part being maintained slightly nearer the longitudinal middle of the path of travel of said stock through said machine than said toe, substantially as described.
15. In a planing-machine, the combination of a side head-hanger, a side cutter-head therefor, a chip-breaker for the latter, a concentric bearing for said chip-breaker taking concentrically about said spindle, a contact part for the stock taking against said chip-breaker for moving all parts of said chip-breaker in concentric lines about the longitudinal axis of said spindle, an adjustable toe for said chip-breaker, and pressure means for said chip-breaker acting against said contact part for relieving said toe from pressure by the stock, substantially as described.
16. In a planing-machine, the combination of a side cutter-head hanger, means for adjusting said hanger transversely of the machine, said hanger having a shelf, a side cutter-head for said hanger, a chip-breaker for said side cutter-head, a roller-bearing for said chip-breaker on said shelf, said roller-bearing taking concentrically about the rotary axis of said side cutter-head, and a lever pivoted on said shelf and moving therewith, said chip-breaker having an inclined face, and said lever having a contact part for said inclined face and for the stock passing through the machine for moving said chip-breaker, substantially as described.
17. In a planing-machine, the combination of a side cutter-head hanger, a shelf therefor, a side cutter-head spindle journaled in said hanger, a cutter-head therefor, a chip-breaker for said cutter-head, said shelf and said chip-breaker having annular rabbets, and antifriction-roller parts in said rabbets, said rabbets being concentric to the rotary axis of said side cutter-head spindle, substantially as described.

18. In a planing-machine, the combination of a side cutter-head hanger, a shelf therefor, means for adjusting said hanger transversely of the machine, a side cutter-head spindle journaled in said hanger, a side cutter-head for said spindle, a chip-breaker for said side cutter-head, said shelf having an annular rabbet 66, said chip-breaker having an annular rabbet 67 and a depending journal-piece 68, said rabbets being concentric to the circle of cut of said side cutter-head and forming a runway 69 for antifriction-balls 70, and retaining means between said depending journal-piece and shelf, substantially as described. 35
19. In a planing-machine, the combination of a side cutter-head hanger, a side cutter-head spindle journaled thereon, a shelf on said hanger, a yielding chip-breaker having roller-bearing connection with said shelf, said roller-bearing being concentric of the rotary axis of said side cutter-head spindle, a lever pivoted on said shelf, said chip-breaker having an inclined face, and a contact-roll 40 on said lever having engagement with said inclined face, the inner edge of said contact-roll being maintained a slightly less distance from the longitudinal middle of stock passing through said machine than the toe of said chip-breaker throughout the yielding movements of said chip-breaker, substantially as described. 45
20. In a planing-machine, the combination of a side cutter-head hanger, means for adjusting the same transversely of the machine, a side cutter-head spindle journaled on said hanger, a shelf for said hanger, a yielding chip-breaker therefor, a bearing for said chip-breaker taking concentrically about the rotary axis of said side cutter-head 50 spindle, a lever pivoted to said shelf, and a contact-roll for stock thereon, said chip-breaker having an inclined face merging into a stop 55 for said roll, substantially as described. 55
21. In a planing-machine, the combination of a side cutter-head hanger, means for adjusting the same transversely of the machine, a side cutter-head spindle journaled in said hanger, a shelf for said hanger, a yielding chip-breaker, a bearing for said chip-breaker taking concentrically about the rotary axis of said side cutter-head spindle, a lever pivoted to said shelf, a contact-roll for stock thereon, said chip-breaker having an inclined face merging into a stop 60 for said roll, and a projection on said shelf limiting inward movement of said lever, substantially as described.

In testimony whereof I have signed my name hereto in the presence of two subscribing witnesses.

JOHN R. THOMAS.
